[57] CLAIM

The ornamental design for a combined soap holder and soap bars therefor, substantially as shown and described.

DESCRIPTION

FIG. 1 is a perspective view of a combined soap holder and soap bars therefor showing my new design;
FIG. 2 is a top plan view of FIG. 1;
FIG. 3 is a front elevational view of FIG. 1;
FIG. 4 is a rear elevational view of FIG. 1;
FIG. 5 is a bottom plan view of FIG. 1;
FIG. 6 is a top plan view of a second embodiment of the design of FIG. 1;
FIG. 7 is a side elevational view of FIG. 6;
FIG. 8 is a bottom plan view of FIG. 6;
FIG. 9 is a top plan view of a third embodiment of the design of FIG. 1;
FIG. 10 is a side elevational view of FIG. 9;
FIG. 11 is a bottom plan view of FIG. 9.
